UNITED STATES PATENT OFFICE.

JULES-FERDINAND HENRY, OF BOULOGNE-SUR-MER, FRANCE.

ROPE-PULLEY MADE IN TWO PARTS.

No. 927,969.

Specification of Letters Patent.

Patented July 13, 1909.

Application filed December 7, 1908. Serial No. 466,418.

To all whom it may concern:

Be it known that I, JULES-FERDINAND HENRY, a citizen of the French Republic, and resident of Boulogne-sur-Mer, France, 5 have invented certain new and useful Improvements in Rope-Pulleys Made in Two Parts, of which the following is a specification.

The present invention relates to a rope-pulley and it more particularly concerns the device for locking together the two parts of a rope-pulley which is made in two parts, such as used with the spars of fishing boats and for similar purposes. The improved 15 locking-device is constructed in such a manner that the two parts of the rope-pulley can be easily unlocked and opened even if the sheave be heavily loaded.

In the accompanying drawing the improved two-parts rope-pulley is shown by way of example in an elevation, the locking-device being represented in section.

The rope-pulley consists of the eye-bolt *a* to the lower transverse part *b* of which the 25 shanks *d*, *e* of the sheave-bearing are pivoted by means of bolts *c*. The sheave *f* is made in two parts which are mounted, the one upon the support *g* of the hook-shaped locking-bolt *h* and the other upon the staple *i* 30 having a hollow *k* adapted to receive the hook of the locking-bolt. The supports *g* and *i* which are made of wrought-steel, are fixed upon the inner surfaces of the shanks *d*, *e* by means of screw-nuts *m* and *n* so that 35 the one stands opposite the other. The support *g* as well as shank *d* have a suitable boring for the reception of the locking-bolt *h* which is revolubly mounted in its support and carries at its outer end a hand-lever *o*. The inner ends of the supports *g*, *i* 40 are cone shaped, the one *g* forming the female and the other *i* the male part.

To lock the rope-pulley which is represented in the drawing in opened position,

hand-lever *o* is turned so that it stands perpendicular to the shank *d* whereby the hook-shaped end of locking-bolt *h* is turned so that it can engage with the staple-opening *k* when the two shanks *d*, *e* are pressed the one toward the other. If now the hand-lever *o* 50 be returned to its original position the hook-shaped end of the locking-bolt *h* gets behind the shoulder formed in the opening *k* and the device is locked, so that the two half-sheaves *f* form a proper sheave adapted 55 to freely turn upon the supports *g*, *i*.

As for certain uses the sheave need not be revoluble the two half-sheaves could be dispensed with, in which case the two supports *g*, *i* are of such a shape that their outer surfaces form the rope-groove.

I claim:

An improved rope-pulley made in two parts, comprising in combination with the eye-bolt having a transverse lower end, two shanks pivoted to said transverse part and having each a boring near its free end, a support fixed in the boring of one of the shanks having a central boring and forming the female part of a cone-coupling, a hook-shaped locking-bolt revolubly mounted in the central boring of said support, a hand-lever fixed upon the outer end of said locking-bolt, a support fixed in the boring of the other shank having a staple opening for the reception of the hook-shaped end of the locking-bolt and forming the male part of a cone-coupling and two half-sheaves revolubly mounted upon said supports so as to form a sheave when the shanks be locked, 75 substantially as described and for the purpose set forth.

In witness whereof I have hereunto set my hand in the presence of two witnesses.

JULES-FERDINAND HENRY.
